WILLIAM J. PANNIER, JR., OF PITTSBURGH, PENNSYLVANIA, ASSIGNOR TO PANNIER BROTHERS STAMP COMPANY, OF PITTSBURGH, PENNSYLVANIA, A CORPORATION OF PENNSYLVANIA

EMBOSSING SHEET METAL

Application filed August 16, 1930. Serial No. 475,765.

My invention refers to the art of embossing or stamping sheet metal or the like, and consists of an improvement in the means for practicing it.

5 In the usual practice of stamping or embossing tags, plates, boxes, containers, etc. of sheet metal, it is customary to subject the sheet metal blank to the action of deforming male and female dies. These may be of 10 metal having corresponding projecting and recessed portions, or of individual type members and a co-acting matrix, or other equally expensive and complicated means, whereby to stamp the blank conformably when subjected to pressure between such pair of male 15 and female members.

In my present improvement I utilize a pair 20 of sheet metal embossing dies which themselves have been first deformed by subjection to pressure between deforming male and female type or other equivalent means so as to produce in the sheet metal coacting and interfitting male and female character forming dies. The sheet metal embossing dies thus 25 formed, of suitably strong and resistant metal, are then used, when suitably mounted, as embossing elements on interposed sheet metal blanks.

In the drawings, showing one preferred 30 embodiment of the invention:

Fig. 1 is a perspective assembly view showing the several co-operating members of an operative installation for practicing my invention;

35 Fig. 2 is a vertical sectional view showing the parts in operative relation when closed;

Fig. 3 is a perspective view of one of the resulting embossed units;

40 Fig. 4 is a plan view of one of the embossing sheet metal blanks before being subjected to the deforming operation of the initial character developing dies;

Fig. 5 is a diagrammatic view showing two 45 such sheet metal members in closed relationship prior to such deforming treatment;

Fig. 6 is a similar view showing the embossing plates as deformed, and illustrating the male and female deforming dies and their action thereon;

50 Fig. 7 is a similar view showing the sides

of the deformed embossing blanks bent upwardly and downwardly for attachment to the operating press members;

Fig. 8 is a similar view showing the deformed sheet metal die members attached to 55 the press members in operative relationship;

Fig. 9 is a similar view showing the embossing members thus mounted and separated, with a sheet metal blank between them ready for embossing;

Fig. 10 is a similar view showing the sheet metal blank after being embossed;

Fig. 11 is a vertical sectional detail view 60 on the line XI—XI of Fig. 2, at one end thereof;

Fig. 12 is a similar view at the opposite end thereof.

Referring to the drawings, A represents the reciprocable head in operative relationship to the lower stationary anvil or base 70 B, of a stamping or embossing machine or press. Slidably or otherwise mounted in said members, as by tongue and groove engagement 2, for easy placement and removal, are the upper coacting pressing heads a and lower supporting anvil or base member head b.

Both the reciprocable head a and the stationary head b are provided at opposite sides 80 with plates 3 secured by screws 4 or otherwise, for the purpose of confining between them and the opposite end faces of each head, the active sheet metal male and female embossing plates C and D respectively, constructed and adapted to operate in the manner hereinafter described.

Each of said sheet metal members C and D is originally flat, of the form shown in Fig. 4, one being the counter-part of the other, with lateral oppositely located flange members 5 adapted to be bent reversely in opposite directions on the line 6 at right angles to the main middle portion C or D, as shown.

Confining plates 3 are under-cut, as indicated at 7, providing just sufficient clearance between them and the side faces of heads C and D to receive the flanges 5 when inserted, the plates 3 being inwardly beveled,

as at 8, to facilitate and guide their entrance.

Flanges 5 are provided with openings 9 suitably located to register with the interlocking balls 10 mounted in sockets 11 against springs 12, which tend to normally thrust the balls outwardly, allowing them to recede when the edges of flanges 5 are inserted, and to spring outwardly in interlocking engagement with holes 9 when the embossing plates are inserted, as in Fig. 2.

In such position the embossing plates will thus be oppositely held with their inner middle flat faces in direct bearing engagement against the heads *a* and *b*, and to be thus maintained in continuously operative relationship to each other for opening and closing towards and from the interposed sheet metal blank E, Fig. 9.

For the purpose of providing a somewhat resilient cushion mounting for the female plate member D, I utilize a bedding or base 13 of rubber or the like, against which the plate D bears, so as to provide interposing resistance between it and the base member *b*. Bedding 13 is inserted in a suitable recess 14 of head *b*, and when the plate D is in interlocked position, as in Fig. 2, the female sheet metal die member is thus retained during operation.

In the diagrammatic views, Figs. 5 to 10 inclusive, I show the successive steps of the several operations.

In providing the sheet metal embossing plates C and D with any desired configuration or character-forming projections and depressions, they are assembled in pairs, one closely against the other and subjected to the deforming action of a male type or die member 15 and a female type or die member 16. As many of such members are used, either in a complete assemblage, or singly by successive operations, as may be desired or preferable, so as to completely develop the entire series of embossing characters throughout so much of the area of plates C and D together, as will transmit to the sheet metal blanks to be operated upon, the desired embossing characters, as indicated in Fig. 3.

A sheet metal blank E, which may be in strip form such as that illustrated in prior patent of Oscar M. Pannier No. 1,764,884, or in any other suitable form, either connected or singly, is interposed between the embossing plates C and D, with the die heads separated, as in Fig. 9.

With the embossing plates thus made and mounted, and with suitable feeding mechanism adjusted to the speed of operation of the press, one blank after another may be quickly brought between the dies of the press, operated upon and then shifted for introduction of a new blank, each of which will thus

produce the desired impression in a definite, clear and well defined manner.

In making the pairs of sheet metal plates C and D, the flanges as described are bent oppositely at right angles in the male and female members respectively. For the purpose of identifying the proper location of each member with respect to the other, in placing in the embossing machine, one particular corner of each flange 5 is cut away or otherwise identified, as by the bevel cut 17, so that the operator may avoid any mistake in quickly adjusting any pair of such embossing plates to the press. By such means I positively prevent the possibility of locating the embossing plates in improper relationship, thereby avoiding any danger of non-registering with resulting mutilation or destruction.

To further ensure exact registering with each other, the side retaining plates 3 are closed at opposite ends, as at 18, 19, beyond the middle clearance space 7 for flanges 5. The special beveled or otherwise shaped corner 17 engages the end abutment 19 while the remaining corners of flanges 5 are preferably rounded, as at 20, for easy insertion in the slots 7, with vertical end bearing portions 21 engaging end abutments 18, as in Figs. 11 and 12.

By means of the above described construction, I am enabled to cheaply and quickly manufacture pairs of sheet metal embossing die members, each having its own individual characters or deforming projections and depressions, each of which pairs is capable of satisfactorily and efficiently embossing several thousand of the thin sheet metal blanks acted upon.

I thereby avoid and save the expense of making a large number of heavy dies in the manner now usually employed, and when worn out, any such particular pair of embossing plates may be readily reproduced in the same manner as above described.

The advantages of the invention and its adaptation to a great variety and range of work will be readily understood and appreciated by all those familiar with the operation of embossing sheet metal. It may be adapted to a great variety of characters, letters, figures, or the like, and is continuously efficient and operative. The invention is in no way limited as to size, design, or other particular features as described and illustrated, and may be changed or varied by the skilled mechanic in adapting it to its intended use, within the scope of the following claims.

What I claim is:

1. Embossing members for action on sheet metal consisting of a pair of sheet metal die members, one having projections and the other having corresponding registering depressions, and quickly detachable resilient interlocking means for mounting said die members in operative relation to each other.

2. Embossing members for action on sheet metal consisting of a pair of sheet metal die members, one having projections and the other having corresponding registering depressions and each having a pair of attaching flanges, and means resiliently engaging said flanges. 70
3. Embossing members for action on sheet metal consisting of a pair of sheet metal die members, one having projections and the other having corresponding registering depressions and each having a common characteristic element to ensure matching in operative relationship. 75
4. In combination with the stamping head of a press having a middle bearing face and transversely arranged retaining plates at opposite sides, a sheet metal embossing die having deformed characters and rectangular flanges inserted between the head and said plates. 80
5. In combination with a stamping head of a press having a middle bearing face and transversely arranged retaining plates at opposite sides, a sheet metal embossing die having deformed characters and rectangular flanges inserted between the head and said plates, and means preventing endwise movement of the die. 85
6. In combination with the stamping head of a press having a middle bearing face and retaining plates at opposite sides and outwardly pressed locking devices, a sheet metal embossing die having flanges inserted between the head and said plates and provided with openings registering with said locking devices. 90
7. In combination with the stamping head of a press having a middle bearing face and retaining plates at opposite sides having limiting abutments, a sheet metal embossing die having flanges inserted between the head and said plates and engaging said abutments. 95
8. In combination with the stamping head of a press having a middle bearing face and retaining plates at opposite sides and spring mounted balls in said sides, a sheet metal embossing die having flanges inserted between the head and said plates and provided with openings registering with said balls for interlocking engagement therewith. 100
9. In combination with the stationary and movable members respectively of a press, heads therefor each having retaining plates at opposite sides and resiliently mounted retaining devices, a pair of embossing plates, one for each head having male and female deforming characters, and provided with terminal flanges for engagement with said retaining plates and devices. 105
10. In combination with the stationary and movable members respectively of a press, heads therefor each having retaining plates at opposite sides and resiliently mounted re- 110
- taining devices, a pair of embossing plates, one for each head having male and female deforming characters, and provided with terminal flanges for engagement with said retaining plates and devices, one of said heads having a resisting bedding of rubber or the like. 115
11. In combination with the stamping head of a press having a middle bearing face and retaining means at opposite sides embodying depressible holding devices, a sheet metal embossing die having quickly attachable and detachable edge portions engageable by said retaining means. 120
12. In combination with the stationary and movable members respectively of a press, heads therefor each having retaining means at opposite sides embodying movable holding devices, a pair of sheet metal embossing plates, one for each member having male and female deforming characters and provided with quickly attachable and detachable edge portions engageable by said retaining means, one of said members having a resilient resistant bedding. 125
13. Embossing members for action on sheet metal consisting of the combination with operating members, of a pair of sheet metal die members, one having projections and the other having corresponding registering depressions and each having quickly detachable resilient interlocking means for separable attachment to one of the operating members. 130

In testimony whereof I hereunto affix my signature.

WILLIAM J. PANNIER, JR.
